UNITED STATES PATENT OFFICE.

PETER REILLY, OF WORCESTER, MASSACHUSETTS, ASSIGNOR TO JOSEPH P. SCHMITT,
OF NEW YORK, N. Y.

SPINDLE-TESTER.

1,129,908.

Specification of Letters Patent. Patented Mar. 2, 1915.

Application filed February 21, 1914. Serial No. 820,173.

To all whom it may concern:

Be it known that I, PETER REILLY, a citizen of the United States, and a resident of Worcester, in the county of Worcester and 5 State of Massachusetts, have invented a new and Improved Spindle-Tester, of which the following is a full, clear, and exact description.

The invention relates to spinning and 10 twisting machines, and its object is to provide a new and improved spindle tester arranged to permit an operator to quickly and accurately ascertain the efficiency or non-efficiency of the spinning and twister spindles without requiring stopping of the 15 machine or removal of the spools or bobbins from the spindles.

In order to accomplish the desired result, use is made of a spring-pressed bar 20 slidable in a handle provided with a scale on which indicates a pointer held on the said bar, the outer end of the bar having a shoe adapted to be engaged with the peripheral face of a running spindle to gradually overcome the 25 force of the driving belt on pressing the shoe against the spindle with a view to bringing the spindle to a stop, the amount of pressure indicated by the pointer on the said scale denoting the running efficiency of the 30 spindle.

A practical embodiment of the invention is represented in the accompanying drawings forming a part of this specification, in which similar characters of reference indicate corresponding parts in both views.

Figure 1 is a sectional side elevation of the spindle tester as applied, the section being on the line 1—1 of Fig. 2; and Fig. 2 is a plan view of the same.

40 In a suitably constructed hollow handle A is mounted to slide a bar B terminating at its outer end in a recessed head B' in which is secured a shoe C, of cork, hard rubber or other suitable material. The outer face of 45 the shoe C is preferably segmental to fit the peripheral face D' of the base of a spindle D, driven in the usual manner by a pulley E and belt F from a suitable source of power.

50 The bar B is pressed on by a spring G held in the hollow handle A to normally hold the bar B in outermost position. On the bar B is secured a pointer H which extends through a slot A' formed lengthwise in the 55 handle A, and the said pointer H indicates

on a scale I arranged exteriorly on the handle A adjacent the slot A'. As indicated in the drawings, the forward portion of the bar B is preferably square and mounted to slide in a correspondingly-shaped bearing 60 A² held on the forward end of the handle A, while the rear portion B² of the bar B is preferably round and is mounted to slide in a bearing A³ at the rear end of the handle A. The rear end of the spring G abuts 65 against the bearing A³ while the forward end of the spring rests against the pointer H to normally hold the bar B in outermost position.

In using the device, the operator takes 70 hold of the handle A and engages the shoe C with the peripheral face of the spindle D, as plainly indicated in the drawings, and then the operator presses the handle A toward the spindle thus causing the handle 75 to slide on the bar B against the tension of the spring G. The operator continues the movement of the handle A toward the spindle D until the shoe C exerts sufficient pressure on the spindle D so that the latter 80 comes to a standstill, and at this time the operator notes the position of the pointer H on the scale I. The scale I indicates the pressure at which the spindle comes to a stop, thus enabling the operator to determine the efficiency of the running spindle 85 relatively to the work to be performed in winding up the yarn or threads on the bobbin or spool held on the said spindle. If the spindle stops below a predetermined 90 pressure, it is necessary to rectify the driving of the spindle correspondingly so that the spindle can only be stopped by the spindle tester when the predetermined pressure is reached.

95 It will be noticed that by the use of this spindle tester it is not necessary to stop the spinning or twisting machine or to remove the bobbin or spool from the spindle while testing the same.

100 Having thus described my invention, I claim as new and desire to secure by Letters Patent:

1. A spindle tester, comprising a hollow handle having openings in its ends and provided with a longitudinal slot and a scale 105 adjacent the slot, one of the said openings being polygonal, a bar having a polygonal end and mounted to slide in the handle with its ends projecting through the openings of 110

the handle, a pointer on the bar and projecting into the slot of the handle and indicating on said scale, a segmental shoe on the end of the polygonal end of the bar and adapted to engage the peripheral face of a spindle, and a spring surrounding the bar in the handle and pressing said bar outwardly.

2. A spindle tester, comprising a hollow handle provided with a slot extending lengthwise in the said handle, a scale on the handle adjacent the slot, a bar mounted to slide in the said handle and terminating at its outer end in a recessed head, a shoe re-

movably held in the said recessed head and 15 adapted to engage the peripheral face of the spindle, a spring in the said handle and pressing the said bar, and a pointer held on the said handle and extending through the said slot, the said pointer indicating on the 20 said scale.

In testimony whereof I have signed my name to this specification in the presence of two subscribing witnesses.

PETER REILLY.
